CHRISTIAN BODMER, OF NEW BRITAIN, CONNECTICUT, ASSIGNOR TO THE STANLEY RULE AND LEVEL COMPANY, OF NEW BRITAIN, CONNECTICUT, A CORPORATION OF CONNECTICUT.

MITER AND TRY-SQUARE.

1,213,578.

Specification of Letters Patent. Patented Jan. 23, 1917.

Application filed May 29, 1916. Serial No. 100,448.

To all whom it may concern:

Be it known that I, CHRISTIAN BODMER, a citizen of the United States of America, residing at New Britain, Connecticut, have 5 invented a new and useful Miter and Try-Square, of which the following is a specification.

My present invention is a combination miter and try-square and the objects of the 10 invention are to provide a simple and practical form of tool which can be readily used at will to serve the functions of a try-square or miter.

A special object is to provide a tool of the 15 above mentioned character having a working blade which may be adjusted as to length to suit different requirements.

In the accomplishment of these objects and others as will later appear, I construct 20 the tool with a stock having a ninety degree or "right angle" straight edge at one side and a forty-five or "miter" straight edge on the opposite side thereof and I provide a working blade which is slidably engaged in the tool stock and is also pivotally secured so that it may be swung from one side of the tool stock over to the opposite side of the tool stock.

A special feature of the invention is the 30 provision of the tool stock with an opening therethrough located between the straight edges at the opposite sides thereof and providing clearance for the end of the blade in swinging over from one side to the opposite side of the tool head.

Another feature is the provision of bearing seats at the opposite ends of said opening providing supports for the blade in the planes of the respective straight edges.

40 A further feature is a special form of slotted bolt for holding the blade in adjusted relation in the head, carrying a pin working in a longitudinal slot in the blade.

In the accompanying drawing I have 45 illustrated the invention embodied in the practical and preferred form but it will be understood that changes and modifications may be made without departing from the true spirit and scope of the invention.

50 In said drawing, Figure 1 is a face view of the tool partly broken to show the bearing seats for the blade and indicating, in dotted lines, the action of swinging the blade from one side over to the opposite side of 55 the head. Fig. 2 is a sectional view taken

substantially on the plane of the line 2—2 of Fig. 1. Fig. 3 is a view of the invention as embodied in a square.

The tool stock 7 is made with a ninety degree face or straight edge 8 at one side 60 thereof and a forty-five degree face or straight edge 9 at the opposite side thereof, the two straight edges converging to a head portion in which the marking blade 10 is secured. This blade is provided with a longitudinally extending slot 11 therein having closed ends and extending usually about half the length of the blade.

The marking blade seats in a slot 12 formed in the head and extending through 70 from the straight edge at one side to the straight edge on the opposite side, bearing seats 13 and 14 for the blade being provided at the opposite ends of the slots in the planes of the respective straight edges. 75

At a point between the bearing seats the tool stock is recessed or formed with an opening as indicated at 15, leaving the two bearing seats separated from each other so that the blade rests on two separate points 80 of support and providing also clearance for the end of the blade when turning the blade over from one side to the opposite side, as will be clear in the dotted positions of the blade shown in Fig. 1. 85

The blade is adjustably held to its seat by a clamping bolt or post 16 seated in a bore 17 in the tool stock and slotted as indicated at 18 to provide arms 19 disposed at opposite sides of and receiving between them 90 the thickness of the blade. A pivot pin 20 connecting these arms works in the slot 11 in the blade and the exposed end of the bolt is usually threaded to receive a clamp nut 21. 95

The use of the device will be clear from the foregoing it being apparent that upon loosening the thumb nut 20 the blade may be easily slid over and secured at any desired length and may further when desired be swung over from a position coöperating with the one straight edge into position at the opposite side of the head coöperating with the other straight edge which makes it possible to adapt the tool to many different requirements. The recess or opening 15 left between the bearing seats is of especial advantage in that it prevents the corners of the blade being injured in the movement of swinging the blade from one side 110

over to the opposite side of the head and also is useful in that it enables the two bearing seats being readily "trued" up, in the course of manufacture, the usual process being, where it is found the slot-forming saw has left one or the other bearing seat 5 too high, to insert a thin blade in the slot having cutting teeth on a portion of its lower edge which can be engaged with the high bearing seat while a plain portion of 10 the blade is bearing on the opposite seat which needs no "truing," the movement of this cutting blade then serving to quickly reduce the high bearing seat to its proper 15 height.

It will be evident that the features of the invention can as well be incorporated in the usual type of try-square as indicated in Fig. 3 where except for the tool stock being designated 7' and the straight edges being designated 8' and 9' the reference 20 characters are the same.

What I claim is:

1. A combined miter and try square comprising a tool stock having convergently arranged mitering and squaring edges and a blade pivotally secured in the head of the tool stock between said edges and adapted to be swung from coöperating relation with 25 one of said edges over to the opposite side of the head into coöperating relation with the other edge with a seat on each side of the pivotal mounting for said blade, said seats being positioned to simultaneously engage one side edge of said blade to definitely establish the angular position of said 30 blade and stock.

2. In a tool of the character set forth, a tool stock having straight edges at opposite 40 sides thereof and a slot extending therethrough from one straight edge to the other straight edge, a blade seated in said slot and formed itself with a longitudinal slot and a clamping bolt mounted in the tool stock and provided with a pivot pin working in the slot 45 in the blade to thereby permit of the blade being swung on said pivot from coöperating relation with the straight edge on one side of the tool over into coöperating relation 50 with the other straight edge on the oppo-

site side of the tool with a seat on each side of the pivotal mounting for said blade, said seats being positioned to simultaneously engage one side edge of said blade to definitely establish the angular position of said 55 blade and stock.

3. In a tool of the character set forth, a tool stock having straight edges at opposite sides thereof and a slot extending therethrough from one straight edge to the other 60 straight edge, a blade seated in said slot and formed itself with a longitudinal slot, a clamping bolt mounted in the tool stock and provided with a pivot pin working in the slot in the blade to thereby permit of the 65 blade being swung on said pivot from coöperating relation with the straight edge on one side of the tool over into coöperating relation with the other straight edge on the opposite side of the tool, said tool stock having an opening extending therethrough located between the straight edges 70 to provide clearance for the end of the blade in swinging over from one side to the opposite side of the tool stock and provided with bearing seats for the blade at the opposite ends of said opening.

4. In a tool of the character set forth, a tool stock having straight edges at opposite sides thereof, an opening therethrough 80 between said straight edges, bearing seats at the opposite ends of said opening and a slot extending through the tool stock from the straight edge at one side to the straight edge at the opposite side thereof, a blade seated in said slot and bearing on said seats at the respective straight edges and bridging the opening between said bearing seats, said blade having a longitudinal slot therein, a slotted clamping post mounted 85 in the tool stock and having side arms embracing the opposite faces of the blade and a pivot pin extending between the side arms and through the longitudinal slot in the blade to thereby hold the blade in lengthwise adjustable relation in the tool stock and permit of said blade being swung over from one side of the tool stock to the other side.

CHRISTIAN BODMER.
